DENSITY CONTROL DEVICE FOR
KNITTING MACHINES

Albert Gee, Elkins Park, Pa., assignor, by mesne assignments, to Haines Hosiery Mills, Inc., Nicetown, Philadelphia, Pa., a corporation of Pennsylvania

Application April 8, 1930, Serial No. 442,500

21 Claims. (Cl. 66—82)

My present invention relates generally to knitting machinery, and has particular reference to a mechanism for automatically controlling the density of an article being knitted, i. e., the lengths of the loops.

A general object of my present invention is to provide a mechanism for automatically making certain adjustments at predetermined times so that the lengths of the loops being knitted will be automatically varied in accordance with a predetermined plan.

In the drawings, I have illustrated my invention as embodied in or applied to a so called full fashioned knitting machine, and will so hereinafter describe it.

In a full-fashioned knitting machine, a series of needles are carried by a needle bar which is capable of moving in several directions, and the density of the knitting i. e., the length of the loops formed by the needles, is controlled by controlling the movement of the needle bar. In the type of machine illustrated in the drawings, the movements of this bar are controlled by mechanism comprising a so called regulating shaft which does not continuously rotate but whose angular position is altered from time to time. In this embodiment it is the angular position of this shaft which determines the density of the knitted article and this has hitherto been controlled manually; and it is an object of my present invention as applied to full-fashioned machines of this character to dispense with the necessity for making slight predetermined adjustments of this shaft by manual operation. Thus, where in such a machine the manual control is in the form of an arm or lever for shifting the angular position of the regulating shaft and thereby controlling the length of the loops being knitted, my present invention provides an automatic mechanism which may be initially adjusted in a predetermined manner, and which mechanism thereafter adjusts said arm or lever at predetermined times to vary the angular position of the regulating shaft.

For the attainment of the objects of my invention, in the exemplified machine, I have illustrated a set of abutments which are individually adapted to co-operate with a control arm of the foregoing character to engage the same and hold it in variable predetermined positions, and which abutments are shown as discontinuous and independent of each other and in the form of a series of spokes having differing lengths, and I provide for the automatic change of these abutments at predetermined times, by means such as a ratchet

and pawl arrangement which controls the rotation of a wheel which carries the aforementioned abutments peripherally thereof.

The automatic operation of the ratchet and pawl arrangement at predetermined times is attained in the above referred to embodiment, by means of a continuous member, such as a chain, carrying a series of projections mounted for individual adjustment at desired spaced intervals, and each arranged to co-operate with a member controlling the operation of the ratchet and pawl arrangement.

The needle bar control is attained by the relationship of the abutments to the control arm of the exemplified machine so that said arm will rest upon an individual abutment under the action of gravity, a spring, or both and the arm is thus caused to assume a predetermined fixed position which thereby determines a predetermined, fixed angular position of the regulating shaft.

In connection with the exemplified application of my invention, I have provided for moving the control arm out of the way of the abutments for a temporary or momentary period during which one abutment is substituted for another, by mounting the control arm upon a spindle and by providing for a rocking movement of the spindle at predetermined times, which rocking movement is imparted to the spindle by the striking action of a rocking member, such as the needle bar arm of the machine, against a roller or the like eccentrically mounted with respect to said spindle. I mount such roller out of the normal path of movement of such rocking member and provide for an interposition of the roller into the path of the rocking needle bar arm at predetermined times, which I illustrate as accomplished by a continuous member or chain provided with individual projections capable of adjustment thereon at desired intervals.

While I have illustrated my invention as embodied in a specific type of machine and for this purpose have referred above to various parts of such a machine and to the co-operation specifically with such parts of a specific embodiment of my invention, it will be understood that the disclosures of this one type and of the specific details of the application of my invention thereto is merely for purpose of an illustrated application of one form of my invention and that my invention is not to be construed as so limited unless called for by the language of the claims.

For the attainment of the foregoing objects

and such other objects as may hereinafter appear or be pointed out, I have constructed a device embodying the features of my invention and illustrated in the accompanying drawings, wherein—

Figure 1 is a front elevational view of a portion of the mechanism of my present invention;

Figure 2 is a cross-sectional view taken substantially along the line 2—2 of Figure 1;

Figure 3 is a fragmentary cross-sectional view taken substantially along the line 3—3 of Figure 1;

Figure 4 is a fragmentary cross-sectional view taken substantially along the line 4—4 of Figure 1;

Figure 5 is an enlarged perspective view of a portion of the mechanism;

Figure 6 is an enlarged fragmentary cross-sectional view taken through a portion of the mechanism shown in Figure 5; and

Figure 7 is a view similar to Figure 2 taken at a different portion of the machine.

In the several figures, I have shown well-known portions of a knitting machine in dot-and-dash lines wherever such portions are shown merely for the purpose of allocating the several shafts and arms which are directly involved in my present invention.

Referring for the moment to Figure 7, it will be observed that I have shown for illustrative purposes a single needle 10 mounted in a needle bar 11. The latter is supported upon an arm or lever 12 pivoted at its lower end 13 to a forwardly extending link 14. The latter is adapted to be brought into pivoted association with a cam lever 15 which is attached at its upper end to the presser shaft 16. I have shown one customary manner of providing a pivot pin 17 upon the lever 15 and providing the link 14 with a series of notches selectively engageable with the pin 17 to vary the effective length of the link 14.

At its lower end, the cam lever 15 is constantly urged rearwardly by a spring 18. The lower end of the lever 15 is also provided with a cam follower or roller 19 adapted to cooperate with a cam 20 mounted upon the main cam shaft 21.

It is the rocking or oscillating motion of the presser shaft 16 which imparts a rocking or presser motion to the needle bar 11 and which controls the length of loops being knitted. Thus, when the cam 20 rotates, it causes the follower 19 to move toward the right and left under the combined action of the cam and the spring 18. This causes the arm 12 to oscillate in a substantially parallel manner, and the provision of the pivot 22 beneath the needle bar 11 causes the needle bar and the needles carried thereby to reciprocate in a substantially horizontal direction.

Beneath the cam lever 15 is a regulating shaft 23 which carries at spaced intervals a series of arms, such as that shown at 24, which are secured to the shaft 23 by means of the set screws 25. The free end of the arm 24 is provided with a stud 26 which bears against the rear face of the extreme lower end of the cam lever 15. Upon viewing Figure 7, it will be obvious that if the regulating shaft 23 were to be moved by a slight degree in a clockwise direction, the roller or follower 19 would be moved slightly away from the cam 20, and this would cause the lever 15 and the needle bar 11 thereafter to oscillate through a smaller range. In other words, the angular position of the regu-

lating shaft 23 controls the length of loops being knitted.

The manner whereby the regulating shaft 23 is angularly displaced at predetermined times is shown in Figure 2. Mounted upon the shaft 23 are two arms 27 and 28, both extending upwardly from the axis of the shaft 23 in a substantially V relationship. The arm 28 is secured to the shaft 23 so as to move with the latter, and the arm 27 is freely mounted upon the shaft 23, but is limited in movement in one direction by contact between a roller carried by it, and a cam on the cam shaft 21, this being the customary construction.

At the upper end of the arm 28 I provide a spindle 29 which carries a cam 30 and a radially projecting control arm 31. The cam bears against a stud 32 adjustably projecting forwardly from the arm 27.

Upon viewing Figure 2, it will be observed that if the arm 31 were given a counter-clockwise movement, the cam 30 would act as a wedge in bearing against the stud 32 and would increase the angle between the arms 27 and 28. This would have the effect of moving the regulating shaft 23 by a very slight degree clockwise. Similarly, if the control arm 31 were moved downwardly clockwise, the shaft 23 would be given a slight counter-clockwise adjustment.

In the illustrated application of my invention, I dispense with the necessity for any manual adjustment of the control arm 31 in the manner which I will now describe.

I provide a spring 33 which extends from the outer end of the arm 31 down to a bracket 34 carried by the arm 28. This spring urges the arm 31 downwardly, but the arm is held in a predetermined stationary position by virtue of the fact that it rests at its midportion upon the abutment 35. The abutment 35 shown in Figure 40 is in the form of a pin or spoke which is screw-threaded into engagement with a wheel or hub 36. The wheel 36 is mounted upon a shaft or spindle 37 which projects forwardly from the arm 28.

A ratchet wheel 38 is also mounted upon the shaft 37, and this ratchet wheel is caused to rotate at predetermined times by the action of a pawl 39. The pawl 39 is pivoted to an arm 40, which is in turn loosely mounted upon the end 50 of the shaft 37. The arm 40 is given a rocking motion by means of the pitman or connecting rod 41 shown in Figure 1.

Referring now to Figure 1, it will be observed that the left end of the connecting rod 41 is provided with the two fixed collars 42 and 43. A third collar 44 is freely slidable along the rod 41, and a compression spring 45 is interposed between the collars 44 and 42.

The collar 44 is formed integrally with an upwardly extending arm 46 which has its upper end engaging the horizontal rod 47 which extends along the full length of the knitting machine. A pair of collars 48 constrain the arm 46 to move horizontally whenever the rod 47 moves.

Extending across the knitting machine, I have added an operating member, such as the chain 49; and in Figure 1, I have shown the left extreme of this chain where it passes around a 70 rotating sprocket 50. The chain 49 is provided with a series of detachable and adjustable projections 51 which are of such a character that they may be spaced at will at desired intervals along the chain.

A pivotal element 52 is medially pivoted as at 53 and is urged into the full-line position of Figure 1 by the spring 54 or the like. The lower free end of the element 52 is normally interposed in the path of the projections 51, while the upper end of the element 52 engages with the rod 47 between two collars 55. Accordingly each projection 51, as it passes the element 52, will cause the latter to rock momentarily in clockwise direction, thereby imparting an axial movement to the rod 47 toward the right, as viewed in Figure 1, this movement being presently followed by a return movement induced by the action of the spring 54.

Upon viewing Figure 1, it will be obvious that this reciprocation of the rod 47 will be transmitted to the rod 41 and will cause the ratchet wheel 38 to advance by an amount equal to one tooth thereof, this advance taking place in counter-clockwise direction, as viewed in Figure 1.

Upon the return of the rod 47 to its normal position, the pawl 39 rides idly over the teeth of the ratchet wheel and is then poised for the next advance.

The spring 45 serves as a buffer in that it will compress and yield should the rotation of the ratchet wheel be impeded.

In Figure 1, I show an arrangement employing abutments 35 in the form of radial spokes of differing lengths. It will be understood that this arrangement of abutments is not essential, however, but is preferable for the reason that each abutment may be individually handled or replaced without necessitating complete disassembling of the apparatus. It will also be obvious that by properly spacing the projections 51 upon the chain 49, a predetermined step-by-step rotation of the ratchet wheel can be provided for, each advance of this wheel causing one abutment to be withdrawn from beneath the control arm 31 and causing the succeeding abutment to be substituted in its place.

In accordance with my invention, the control arm 31 is momentarily moved away from the abutments each time an advance of the latter is to take place, this momentary withdrawal of the arm being provided for so that there will be no interference between the arm 31 and the abutment beneath it until after a predetermined abutment has come to rest in the path of the descending arm 31.

To provide for this momentary adjustment of the arm 31, I mount the same upon the spindle 29. At one end of this spindle I provide the radial arm 57 which carries the pin 58. The pin 58 is substantially parallel to the spindle 29 and is eccentric with respect thereto. Mounted upon it is the roller 59 which is engaged by a yoke 60. The roller 59 is loose upon the pin 58 so that a movement of the yoke 60 is adapted to shift the roller axially of the pin 58.

The roller 59 is positioned closely adjacent the lower end of the needle bar arm 61, this arm extending upwardly, as shown in Figures 2 and 3, and terminating at its upper end in engagement with the needle bar shaft 62. Midway of the needle bar arm 61 is mounted a follower roller 63 adapted to be acted upon by the cam 64. The latter is mounted upon the cam shaft 21 and causes the needle bar arm 61 to rock at predetermined times, this movement of the needle bar arm being one which is incident to the normal operation of the knitting machine.

In my present apparatus, I resort to the normal

oscillation of the needle bar arm and utilize this arm as an oscillating or rocking member. Accordingly, I will not describe the reasons why the needle bar arm is rocked, it being sufficient for my present purposes to explain that the lower end thereof is constantly urged rearwardly by the spring 65, but is caused at predetermined regular times to advance forwardly.

I mount a stud 66 (Figure 5) adjacent the lower end of the needle bar arm 61, this stud being adapted to swing forwardly across the axis of the pin 58. At predetermined times, the roller 59 is interposed in the path of the stud 66 and the latter at that time strikes the roller 59 and rocks the spindle 29 in counter-clockwise direction, as viewed in Figure 3. Such rocking of the spindle 29 causes the arm 31 to be raised against the action of the spring 33, but immediately after it is raised it returns downwardly under the action of the spring 33. This raising and lowering of the arm 31 will continue as long as the roller 59 is held in the path of the stud 66.

To advance the roller 59 at predetermined times, as above described, I mount the yoke 60 upon a horizontal rod 67 substantially parallel to and adjacent to the rod 47 previously described. This is clearly illustrated in Figure 5.

To shift the rod 67 axially at predetermined times and thereby to shift the roller 59 into the path of the stud 66, I provide a second continuous member in form of a chain 68, continually driven as is the chain 49, and I provide for the adjustability thereon of projections 69 similar to the projections 51 previously described. The projections 69 engage with a pivoted element (not shown) which is similar to the element 52 and which, when encountered by each projection 69, causes the rod 67 to move toward the right, as viewed in Figure 1, and thereafter to return toward the left. When the rod 67 moves toward the right, it will obviously move the yoke 60 with it and shift the roller 59 into the path of the stud 66.

The projections 69 are preferably made longer than the projections 51, or they may be made duplex in character so that the roller 59 will be held in the path of the stud 66 for a sufficient period of time to oscillate the spindle 29 two successive times. This assures a proper advance of the abutments 35.

It will thus be seen that I have provided a mechanism which is of an extremely simple character and which obviates the necessity for any manual adjustment whatsoever of the regulating shaft. If a change of loop size is desired at predetermined times during the knitting operation, it is only necessary to arrange the abutments 35 in a proper sequence or to provide them with predetermined lengths, and to adjust the projections 51 and 69 at suitable spaced intervals along the chains 49 and 68. Thereafter, at a predetermined time, the roller 59 will be shifted and then struck; the arm 31 will thereupon be swung upwardly for a moment; and during this procedure, the wheel 38 will have been rotated to interpose a different abutment in the path of the arm 31. Each abutment as it is thus advanced is held in proper position by means of the spring-pressed detent 70 illustrated in Figure 4 and adapted to engage between each two adjacent abutments. Accordingly, after the roller 59 has again been withdrawn to its normal position, the arm 31 will rest upon an abutment of predetermined

different size and will cause the regulating shaft 23 to assume a predetermined angular position which corresponds to a desired length of loop.

It will be obvious that changes in the details herein illustrated and described for the purpose of explaining the nature of my invention may be made by those skilled in the art without departing from the spirit and scope of the invention as expressed in the appended claims. It is therefore intended that these details be interpreted as illustrative, and not in a limiting sense.

Having thus described my invention and illustrated its use, what I claim as new and desire to secure by Letters Patent is—

1. In a knitting machine, a regulating shaft whose position determines the length of loops being knitted, an arm supported on said shaft, a set of different abutments individually adapted to engage with said arm and thereby hold said arm and said shaft in predetermined different positions, respectively, and means for automatically advancing selected abutments into engagement with said arm at predetermined times, respectively; said means comprising a continuous moving member, spaced projections on said member, a movable element encountered by and moved by said projections, and transmission means interposed between said element and said abutments for advancing the latter; said transmission means including a yieldable buffer adapted to yield should said abutments resist advance thereof.

2. In a knitting machine, a regulating shaft whose position determines the length of loops being knitted, an arm supported on said shaft, a set of different abutments individually adapted to engage with said arm and thereby hold said arm and said shaft in predetermined different positions, respectively, said abutments comprising a set of radially arranged rods of different lengths and a wheel for carrying them, and means for automatically rotating said wheel to advance successive radial rods into engagement with said arm at predetermined times, respectively, said means being capable of yielding in the event of impedance to the rotation of the wheel.

3. In a full-fashioned knitting machine having a needle-bar presser lever and an operating shaft; a loop regulating mechanism comprising a regulating shaft, a stop arm for said presser lever fixed to said shaft, and stop arm setting means comprising a cam-operated loose arm and a fixed shaft-rocker arm, a rotatably mounted disc carried by one of said arms and having a circular series of spacing contacts of varying radial projection adapted to vary the relative positioning of said loose and rocker arms, and pattern controlled means adapted to impart rotative movements to said disc.

4. In a full fashioned knitting machine having a needle-bar presser lever and an operating shaft; a loop regulating mechanism comprising a regulating shaft, a stop arm for said presser lever fixed to said shaft, and stop arm setting means comprising a cam-operated loose arm and a fixed shaft-rocker arm, a rotatably mounted disc carried by one of said arms and having a circular series of spacing contacts of varying radial projection adapted to vary the relative positioning of said loose and rocker arms, a ratchet connection to said disc adapted to impart a step-by-step rotation thereof and pattern

controlled means for actuating said ratchet connection.

5. In combination with a full fashioned knitting machine having a needle bar and a cam shaft, a loop length regulating mechanism comprising a cam-actuated presser arm for said needle bar, a rockable regulating shaft having a fixed stop arm for said presser arm, a loose and a fixed arm on said regulating shaft having an adjustable contact engagement, a regulator cam on said cam shaft adapted to rock said shaft in accord with adjusted contact of said loose and fixed arms, and pattern controlled means for determinedly adjusting the contact of said loose and fixed regulator shaft arms to variably space said arms angularly and thereby correspondingly move the regulator shaft.

6. Loop regulating mechanism for flat knitting machines comprising in combination, a loop regulating shaft, an arm free on said shaft and having a roller cooperative with a rotary cam on the cam shaft of the machine, a companion arm fast on the regulating shaft and carrying an eccentric cam in contact with the free arm aforesaid, and means for variably rocking the eccentric cam to variably space the two arms angularly with attendant rocking of the regulating shaft and change in the size of the fabric loops being knitted.

7. Loop regulating mechanism for flat knitting machines comprising in combination, a cam shaft with a rotary cam thereon, a loop regulating shaft, an arm free on said shaft and having a roller to cooperate with the rotary cam aforesaid, a companion arm fast on the regulating shaft and carrying an eccentric cam in contact with the free arm aforesaid, an arm on the axis of the eccentric cam, a wheel on the fast arm aforesaid having radial projections of different lengths effective upon the eccentric cam arm, and means for periodically racking the wheel for substitution of one radial projection thereof for another with attendant rocking of the regulating shaft and change in the size of the fabric loops being knitted.

8. Loop regulating mechanism for flat knitting machines comprising in combination, a cam shaft with a rotary cam thereon, a loop regulating shaft, an arm free on said shaft and having a roller to cooperate with the rotary cam aforesaid, a companion arm fast on the regulating shaft and carrying an eccentric cam in contact with the free arm aforesaid, an arm on the axis of the eccentric cam, a wheel on the fast arm aforesaid having radial projections of different lengths to influence the eccentric cam arm, a control chain, a lever periodically actuated by cam lugs on the chain, and means actuated through movement derived from the lever to periodically rack the wheel aforesaid with attendant substitution of one radial projection thereof for another and resultant change in the size of the fabric loops being knitted.

9. Loop regulating mechanism for flat knitting machines comprising in combination, a cam shaft with a rotary cam thereon, a loop regulating shaft, an arm free on said shaft and having a roller to cooperate with the rotary cam aforesaid, a companion arm fast on the regulating shaft and carrying an eccentric cam in contact with the free arm aforesaid, an arm on the axis of the eccentric cam, a wheel on the fast arm aforesaid having radial projections of different lengths to cooperate with the eccentric cam arm, a pair of control chains, a lever intermittently

actuated by cam lugs on one of said chains to withhold the eccentric cam arm from the wheel at pre-determined times, and another lever actuated by cam lugs on the other chain to concurrently rack the wheel aforesaid with attendant substitution of one radial projection thereof for another and resultant change in the size of the fabric loops being knitted.

10. In a flat knitting machine having loop forming mechanism and a rotatable shaft moving in timed relation thereto; loop regulating mechanism comprising a rotary cam on said shaft, a loop regulating shaft, a rockable member having cam follower means for engagement with said rotary cam, a second rockable member operatively connected to the regulating shaft for rocking the shaft, and carrying an eccentric cam in contact with the first rockable member, and means for variably turning the eccentric cam to vary the angular relation between said members with attendant rocking of the regulating shaft and change in the size of the fabric loops being knitted, said means operating in timed relation to said loop forming mechanism.

25. Loop regulating mechanism for flat knitting machines including in combination, a loop regulating shaft, a pair of relatively movable cooperating members for varying the angular position of said shaft, means for variably positioning said members relative to each other, including a pair of elements provided with coacting camming surfaces, means for maintaining said coacting surfaces in constant contact with each other, and means for moving one of said elements so as to change the point of contact of said camming surfaces and thereby vary the angular relation between said members.

40. Loop regulating mechanism for flat knitting machines including in combination, a loop regulating shaft, a pair of relatively movable cooperating members for varying the angular position of said shaft, means for variably positioning said members relative to each other, including a pair of elements provided with coacting camming surfaces, means for maintaining said camming surfaces in constant contact with each other, and pattern means for moving one of said elements so as to change the point of contact of said camming surfaces and thereby vary the angular relation between said members.

55. Loop regulating mechanism for flat knitting machines including in combination, a loop regulating shaft, a pair of relatively movable cooperating members for varying the angular position of said shaft, means for variably positioning said members relative to each other including an element on each of said members, said elements being provided with coacting camming surfaces, means for maintaining said camming surfaces in constant contact with each other, and means for imparting selective movements to one of said elements so as to change the point of contact of said camming surfaces and thereby vary the angular relation between said members.

65. Loop regulating mechanism for flat knitting machines including in combination, a loop regulating shaft, a pair of relatively movable cooperating members on said shaft for varying the angular position of the latter, means for variably positioning said members relative to each other, including a fixed element on one of said members and a movable element on the other member, said elements being provided with coacting camming surfaces, means for yieldingly urging said elements toward each other so as to main-

tain said camming surfaces in constant contact, and pattern means for selectively positioning said movable element so as to change the point of contact of said camming surfaces and thereby vary the angular relation between said members. 5

15. In a knitting machine, a regulating shaft whose position determines the length of the loops being knitted, an arm supported on said shaft, a set of abutments individually adapted to engage with said arm to hold it and said shaft in pre-determined different positions respectively, and means for automatically advancing said abutments respectively into engagement with said arm at predetermined times, said means having the capacity to yield in the event that the movement of said abutments is impeded.

16. In a knitting machine, a cam shaft with a rotary cam thereon, a loop regulating shaft; an arm free on said regulating shaft and having a roller to cooperate with the rotary cam aforesaid, a companion arm fast on the regulating shaft and carrying a rotary eccentric cam in contact with the free arm aforesaid, an actuating arm on the axis of the eccentric cam, a set of abutments also carried by the companion arm 35 and adapted to individually engage the actuating arm, thereby to hold it and the eccentric cam in predetermined different positions, means for automatically advancing selected abutments into engagement with said actuating arm at predetermined times, and means for moving the actuating arm momentarily away from said abutments during each abutment advance.

17. In a knitting machine, a cam shaft with a rotary cam thereon, a loop regulating shaft, an arm free on said shaft and having a roller to cooperate with the rotary cam aforesaid, a companion arm fast on the regulating shaft and carrying a rotary eccentric cam in contact with the free arm aforesaid, an actuating arm 40 on the axis of the eccentric cam, a wheel also carried by the companion arm and having a series of radial abutments of different lengths adapted to individually engage the actuating arm and thereby hold it and the eccentric in predetermined positions, means for intermittently rotating the wheel to advance selected abutments thereof into engagement with the said actuating arm at predetermined times, and means for moving the actuating arm momentarily away 50 from said abutments during each rotative shift of the wheel.

18. A knitting machine in accordance with claim 16, including a chain, and interposed connections operated by projections on the chain to automatically advance the abutments and to move the actuating arm temporarily away from the abutments during each abutment advance.

19. A knitting machine in accordance with claim 17, including a chain, and interposed connection operated by projections on the chain to automatically rotate the abutment wheel intermittently, and to move the actuating arm temporarily away from the abutments during the rotative shifts of the wheel. 65

20. In a knitting machine, a cam shaft with a rotary cam thereon, a loop regulating shaft, an arm free on the regulating shaft and having a roller to cooperate with the rotary cam aforesaid, a companion arm fast on the regulating shaft and carrying a rotary eccentric cam in contact with the free arm aforesaid, an actuating arm on the axis of the eccentric cam, a set of abutments carried by the companion arm and adapted to individually engage the ac- 75

tuating arm, thereby to hold it and the eccentric cam in predetermined different positions, and means for automatically advancing selected abutments into engagement with said arm at predetermined times.

21. In a knitting machine, a cam shaft with a rotary cam thereon, a loop regulating shaft, an arm free on the regulating shaft and having a roller to cooperate with the rotary cam aforesaid, a companion arm fast on the regulating shaft and carrying a rotary eccentric cam in contact

with the free arm aforesaid, an actuating arm on the axis of the eccentric cam, a wheel also carried by the companion arm and having a series of radial abutments of different lengths and adapted to individually engage the actuating arm thereby to hold it and the eccentric cam in predetermined positions, and means for intermittently rotating the wheel to advance selected abutments into engagement with the actuating arms at predetermined times.

ALBERT GEE.

10
